UNITED STATES PATENT OFFICE.

ALBERT COHN AND LOUIS H. DEBS, OF CHICAGO, ILLINOIS.

ELECTRIC-LIGHTING FIXTURE.

1,225,411.

Specification of Letters Patent.

Patented May 8, 1917.

Application filed December 1, 1916. Serial No. 134,299.

To all whom it may concern:

Be it known that we, ALBERT COHN and LOUIS H. DEBS, citizens of the United States, residing at Chicago, in the county of Cook and State of Illinois, have invented certain new and useful Improvements in Electric-Lighting Fixtures, of which the following is a specification.

This invention relates to improvements in electric lighting fixtures and, while certain features of the invention are applicable to wall or ceiling fixtures, the invention refers more especially to a fixture to be used upon a pedestal lamp, such as a floor lamp, table lamp or the like.

A fixture of this character includes a shell or casing and nipples projecting through openings in the shell and threaded to receive and support the sockets which carry the incandescent lights. Difficulty has heretofore been experienced with such fixtures by reason of the fact that the nipples are sometimes wrenching from the shell by the electric lamp socket receiving an accidental blow. It is one of the objects of our invention to produce a structure wherein the lamp-socket-supporting nipples are mounted in a novel and improved manner so that the fixture will be materially strengthened and the nipples cannot be torn from the shell.

Another object of our invention is to improve fixtures of this character by reducing the number of parts to a minimum and, in this connection, the invention has reference to a special unitary bracket device which is mounted within the shell and provides supports for the nipples and for the stud by which the cover of the shell is secured in place.

Further objects and advantages relating to details of construction will be pointed out in the following description.

In the accompanying drawings, Figure 1 is a vertical central section through a lighting fixture embodying the features of our invention. Fig. 2 is a detail plan view of the unitary bracket device.

We have shown in the drawings and will herein describe in detail the preferred embodiment of our invention, but we would have it understood that the invention is not limited to this specific disclosure. We aim to cover in the appended claims all modifications and equivalents falling within the scope of the invention.

In the drawings, the reference numeral 1

designates the upper end of a pedestal lamp, 2 being the central bore through the pedestal to receive the electric-current-supplying wires. The fixture, in accordance with our present invention, comprises a hollow stem or pipe 3 which is suitably mounted on the base 1 in alignment with the bore 2, the mounting means preferably comprising an attaching base 4 which may be of any common or preferred construction and may be fixed to the base 1 by suitable fastening devices as screws 5.

The stem 3 is arranged to support at its upper end a shell or bowl 6 having a cover 7, and within this shell is a bracket device which, in the present instance, comprises a base or central portion in the form of a washer 8. The shell 6 and bracket device may be mounted upon the stem 3 in different ways, the means herein shown for that purpose comprising a depending bushing 9 on the washer which is threaded onto the upper end of the stem 3. The lower end of said bushing may if desired be upset or flared 80 outwardly to engage beneath and around the shell at the edge of the opening for the stem.

The lamp-socket-attaching nipples are indicated at 10 and are carried by the base 8 or washer 8, in this instance through the medium of arms 11 projecting radially from the edge of the washer, said washer, arms and nipples in the preferred construction being formed of an integral piece of sheet metal. The nipples 10 pass outwardly through openings in the shell 6 and have annular stop shoulders 12 on their inner ends to overlie the edges of such openings. The electric lamp sockets are threaded 95 upon the outer ends of the nipples and are supported thereby. A portion of one socket is indicated at 13. The number of nipples and sockets may be varied to suit requirements.

Heretofore these nipples have been formed separate from each other and from the other parts of the fixtures and have been secured in the openings in the shell by merely upsetting or riveting the nipples to clench 105 them to the shell or by soldering the nipples to the shell. It has been found in practice that it is impossible to fix the nipples in place in this manner with sufficient security to prevent the nipples from being wrenching 110 or torn out of their openings in case an accidental blow of any considerable force is ap-

plied to the lamp socket. In our construction the nipples are attached to and are supported by the central washer-like member 8 of the bracket so that any strain upon the nipples is taken up by said central member and the arms 11. A very strong and rigid construction is thus provided which will withstand severe shock without endangering the security of the mounting.

10 In lamp fixtures of this character the shell and its cover may form the support for the framework of the lamp shade. Referring to Fig. 1, 14 designates a central plate and 15 radiating arms or braces constituting part of the shade framework, the plate 14 having a central opening therein registering with a central opening in the shell cover 7. Such cover and shade frame are secured to the body of the shell by means of a threaded 20 stud 16 passing upwardly through said parts and having an ornamental nut 17 threaded on its upper end above the plate 14. This threaded stud may be mounted in the shell in different ways, but preferably it 25 is formed integral with the central washer 8, the stud proper being carried by a finger 18 extending upwardly from one edge of the washer. The stud may be formed by curling, drawing or rolling the end of the piece 30 of sheet metal from which the finger as a whole is made.

By making the central washer 8, nipples 10 and stud 16 out of a single piece of sheet metal, a rigid, cheap, convenient and very 35 satisfactory bracket device is provided and many of the difficulties experienced with prior devices are eliminated. It will be noted that the finger 18 for the threaded stud takes up but very little room and leaves 40 ample space above the washer to receive the wires which lead up through the stem 3 and branch through the nipples 19 to the electric sockets.

Inasmuch as the special bracket device including the stud 16 and nipples 10 is fixed 45 upon the stem 3, it will be seen that the shell 6 will be secured to the stem through the medium of the nipples and when the nut 17 is turned down on the stud to bear upon the 50 cover for the shell, the cover and the shell will be firmly clamped without any special means for attaching the shell to the stem 3. The washer 8 and nipples 10 may thus constitute means for attaching the shell to the 55 stem, while the stud 16 and nut 17 constitute means for binding the parts in place.

We claim as our invention:

1. In a lighting fixture, a bracket comprising a central supporting member, a plurality of projecting arms, and a socket-supporting nipple carried by each of said arms, said arms being integral with said central member.

2. In a lighting fixture, a unitary bracket 65 device comprising a washer, a plurality of

projecting arms, and a socket-supporting nipple integral with each of said arms, said arms being integral with said washer.

3. In a lighting fixture, a bracket comprising a washer, a socket-supporting nipple 70 carried thereby, and a stud and supporting finger therefor integral with said washer.

4. In a lighting fixture, a bracket comprising a washer, a plurality of arms integral therewith, a socket-supporting nipple 75 carried by each of said arms, a stud, and a supporting finger integral therewith and integral with said washer.

5. In a lighting fixture, a unitary bracket device comprising a central supporting 80 member, a plurality of nipples, and a threaded stud all formed in a unitary piece.

6. In a lighting fixture, a bracket comprising a centrally located washer, a plurality of radially projecting arms integral 85 therewith, a lamp-supporting nipple carried by each of said arms, a stud axially aligned with said washer, and a supporting tongue therefor integral with said washer.

7. An electric lighting fixture comprising, in combination, a shell having apertures 90 therein, nipples in said apertures, and a supporting member in the shell to which said nipples are secured.

8. An electric lighting fixture comprising, 95 in combination, a shell having apertures therein, nipples extending through the apertures, a hollow supporting stem, and a central supporting member mounted on said stem and carrying said nipples.

9. An electric lighting fixture comprising, in combination, a shell having apertures 100 therein, nipples passing through said apertures, a supporting stem, and a washer mounted on said stem and formed integral 105 with said nipples.

10. An electric lighting fixture comprising, in combination, a casing having apertures 110 therein, a central supporting member in the casing, and nipples radially positioned with respect to said central supporting member and integral therewith, said nipples passing through the apertures in the shell.

11. An electric lighting fixture comprising, 115 in combination, a shell having apertures therein, a central supporting member in the shell, nipples formed integral with said central member and passing out through said apertures, lamp sockets carried 120 by said nipples outside of said shell, and a hollow supporting stem upon which said shell and said central member are mounted.

12. An electric lighting fixture comprising, 125 in combination, a shell, a cover therefor, a special bracket device in said shell comprising a central supporting member, nipples integral therewith and passing out through apertures in the shell, a hollow supporting stem on one end of which said shell 130

and said central member are mounted, a finger integral with said central member and having an integral threaded stud thereon passing out through the cover of the shell, and a nut threaded on the outer end of said stud and arranged to bear upon the cover.

18. A lighting fixture having, in combination, a shell, a hollow supporting stem therefor, the shell having an aperture, a nipple in the aperture, a washer in the shell regis-

tering with said stem, said nipple and washer being formed of an integral piece of metal, a cover for the shell, a threaded securing stud fixed in the shell and passing 15 upwardly through the cover, and a nut threaded on said stud and holding the cover in place.

In testimony whereof we have hereunto set our hands.

ALBERT COHN
L. H. DEBS.
